UNITED STATES PATENT OFFICE.

ALICE HEWETT, OF WAKONDA, SOUTH DAKOTA.

MOTHPROOF CABINET.

Application filed March 11, 1924. Serial No. 698,437.

To all whom it may concern:

Be it known that I, ALICE HEWETT, a citizen of the United States, residing at Wakonda, in the county of Clay and State of South Dakota, have invented certain new and useful Improvements in Mothproof Cabinets, of which the following is a specification.

This invention relates to new and useful improvements in cabinets which are particularly adapted to receive and support various pieces of wearing apparel and has for its principal object to provide a means for preventing any possibility of moths or other insects from entering the cabinet.

15 A further object of the invention is to provide a cabinet of the above mentioned character, wherein a packing is adapted to extend beyond the outer face of the cabinet around the marginal edge of the opening formed in the compartment thereof and adapted to co-operate with the doors provided for the opening, whereby a tight fit is provided between the door and the cabinet for preventing the entrance therethrough of 25 any insects such as moth or the like.

A still further object of the invention is to provide means in connection with the doors for permitting the same to be readily opened whenever desired and in case the 30 doors have become stuck or hard to open.

A still further object of the invention is to provide a cabinet of the above mentioned character, which is simple in construction, inexpensive, strong and durable and further, 35 well adapted for the purposes for which it is designated.

Other objects and advantages of this invention will become apparent during the course of the following description.

40 In the accompanying drawings forming a part of this specification and in which like numerals designate like parts throughout the same,

Figure 1 is a front elevation of my improved cabinet with parts broken away,

Figure 2 is a vertical sectional view taken on line 2—2 of Figure 1,

Figure 3 is a detail fragmentary section taken on line 3—3 of Figure 1,

50 Figure 4 is a fragmentary detail view of a portion of the packing strip, and

Figure 5 is a detail perspective view of a supporting bracket, and

55 Figure 6 is a fragmentary sectional view taken on line 6—6 of Figure 1.

In the drawings wherein for the purpose

of illustration there is shown the preferred embodiment of my invention, the numeral 1 designates generally a cabinet which is formed of any suitable material, preferably wood and the same comprises the main section 2 and the upper section 3, the upper section being removably supported on top of the main section in any convenient manner and being also formed of substantially the same material. Formed in the front face of the main section 2 of the cabinet 1, are the openings 4 and 5, respectively, and the same extend for substantially the full length of the main section 2 in the manner as clearly shown in Figure 1 of the drawings. The openings provide a means whereby access to the interior of the cabinet may be had, and co-operating with these openings are the doors 6 and 7, respectively, which are hinge- 75 dly mounted on the front face of the main section 2 of the cabinet 1 as illustrated at 8 in the drawings.

Secured to the inner walls of the main section 2 of the cabinet 1 and extending over the entire surfaces thereof is the lining 9. This lining is preferably formed of galvanized sheet metal although it is to be understood that any other suitable material may be substituted therefor, and I do not wish 85 to limit myself to the particular kind of lining to be used in order to carry out the purposes and objects of the present invention. The lining 9 is also adapted to extend around the marginal edges of the openings 90 4 and 5 in a manner as shown at 10 in the drawings having reference more particularly to Figure 3, and the outer portions of the lining 9 are further adapted to be provided with channeled portions 11. The latter are 95 preferably seated in similarly shaped channels or grooves 12 which extend around the marginal edges of each of the openings and is formed in the front face of the cabinet.

Adapted to be disposed within the channeled portions 11 is the inner portion of the packing 13. The packing 13 is also formed of any suitable material, preferably rubber, and as clearly shown in the drawings, the outer portion thereof extends beyond 105 the outer face of the lining which extends around the marginal edges of the openings 4 and 5, respectively. The purpose of this construction will also be hereinafter more fully described.

Co-operating with the outwardly extending portions of the packing 13 is the groove

or channel 14 which is formed in the inner face of each of the doors around the marginal edges thereof, and the manner in which the outwardly extending portion of the packing 13 fits within the groove 14 provided in each of the doors is clearly shown in Figure 3 of the drawings. In this manner, it will be readily apparent that when the doors are in a closed position with respect to the openings 4 and 5 respectively, the rubber packing 13 will fit snugly in the grooves provided in the inner face of the doors thereby closing all of the crevices or openings between the door and door casing 15 or opening therefor.

The usual fastening means which is employed in connection with securing the doors in closed position with respect to the openings is illustrated at 15 in the drawings, and 20 as the same may be of any well known construction, it is not thought necessary to further describe the same. The upper section 3 of the cabinet 1 is also provided with the hinged sections 16 and 17, respectively, 25 and a latch illustrated at 18 is adapted to be associated therewith for holding the same in a locked position. Supported in the upper portion of the main section 2 of the cabinet 1 between the front and rear walls thereof 30 is the transversely extending post or bar 19 from which is adapted to hang the hanger 20 on which may be supported the co-hangers supporting the usual pieces of garment thereon. A bar 19 and hanger support 35 20 of the character above described is adapted to be arranged in each side of the cabinet so as to enable the clothes hanging therein to be properly supported in a suspended position.

40 It will thus be seen from the foregoing description, that a cabinet has been provided wherein a tight fit between the door and the openings therefor in the cabinet provided, are to prevent any possibility of moth or the like from entering the cabinet and damaging the pieces of apparel contained therein. Furthermore, there will be no possibility of any dust or the like entering through the openings between the door and door casing 45 50 as is the case with the cabinets now in use.

If difficulty is experienced in opening the doors of the cabinet, the person may easily release the door from its stuck position within the door casing by actuating the thumb screw 21 the inner end of which is threaded and extends through the threaded opening 22 provided in the angular plate 23, the latter being supported in the cut-out portion on the upper corner of the door in the manner 55 60 as clearly shown in the drawings. The inner end of the thumb screw 21 will engage the outer portion of the lining 9 and by turning the thumb screw in one direction, the door upon which the same is mounted 65 70 will be caused to be moved outward from

engagement with the rubber packing thus enabling the person to more easily open the door.

By providing a cabinet of the above mentioned character, various pieces of wearing apparel may be kept therein without danger of the same being damaged by moth or the like, and furthermore, clothes will be kept in a clean condition for an indefinite period provided of course that the doors are kept 75 in a closed position. The simplicity of my device enables the same to be manufactured at a minimum cost and is also easily operated.

While I have shown the preferred embodiment of my invention, it is to be understood that various changes in the size, shape and arrangement of parts may be resorted to without departing from the spirit of the invention and the scope of the appended claims.

Having thus described my invention, what I claim is:—

1. A cabinet of the class described provided with a compartment, the latter having an opening therefor, a lining within said compartment, said cabinet, having a groove formed in the outer face thereof adjacent the marginal edges of said opening, said lining extending around the marginal edges of said opening, and having a portion there- 95 of fitting in said groove forming a pocket, a packing strip seated in said pocket and extending beyond the outer face of said cabinet, and a door for said opening having a groove formed in the inner face thereof around the marginal edges of the same and adapted to receive the outwardly extending portion of said packing member when the door is closed.

2. A cabinet of the class described provided with a compartment, the latter having an opening therefor, a lining within said compartment, said cabinet having a groove formed in the outer face thereof adjacent the marginal edges of said opening, said lining extending around the marginal edges of said opening, and having a portion there- 105 of fitting in said groove forming a pocket, a packing strip seated in said pocket and extending beyond the outer face of said cabinet, and a door for said opening having a groove formed in the inner face thereof around the marginal edges of the same and adapted to receive the outwardly extending portion of said packing member when the door is closed, and means for facilitating 110 115 the opening of said door.

3. A cabinet of the class described provided with a compartment, the latter having an opening therefor, a lining within said 125 compartment, said cabinet having a groove formed in the outer face thereof adjacent the marginal edges of said opening, said lining extending around the marginal edges of said opening, and having a portion there- 130 135

of fitting in said groove forming a pocket, a packing strip seated in said pocket and extending beyond the outer face of said cabinet, a door for said opening having a groove formed in the inner face thereof around the marginal edges of the same and adapted to receive the outwardly extending portion of said packing member when the door is closed, means for facilitating the opening of said door, said means comprising a bracket supported in the upper corner of said door and having a threaded opening extending therethrough, and a thumb screw threaded through said opening in said bracket and adapted to engage the outwardly extending portion of said lining.

In testimony whereof I affix my signature.

ALICE HEWETT.
